VARIABLE-VOLTAGE TRANSFORMER

Application filed February 20, 1926. Serial No. 89,775.

Our invention relates to electrical translating devices and particularly to transformers for delivering variable voltage to testing instruments. One object of our invention is to provide a transformer that shall be capable of delivering a variable voltage over a wide range.

Another object of our invention is to provide a transformer for testing instruments such that an operator may closely regulate the terminal voltage thereof.

A further object of our invention is to provide a transformer for delivering a variable voltage to testing instruments such that the operator may vary the applied voltage by a very large number of graduations as distinguished from a succession of relatively few predetermined steps.

In electrical testing and measuring apparatus it is frequently necessary to employ the same instruments for widely different calculations and when such calculations depend upon voltage as a factor, it becomes necessary that a transformer shall be capable of developing a continuously varying voltage ratio, the characteristic curve of which is much smoother than that obtained by varying the tap connections of one of the transformer windings through a succession of predetermined steps.

We obtain the foregoing results by employing a plurality of auxiliary windings, one of which is wound on the same core leg as one of the windings of the secondary circuit. These auxiliary windings are connected to a common variable burden so that it is possible to short-circuit either one of the auxiliary windings or to cause it to carry the entire variable burden. Accordingly, as the load on the auxiliary coil that is mounted adjacent to the secondary coil varies, the energization, and consequently the voltage output, of the secondary coil varies proportionally. In the accompanying drawings,

Fig. 1 is a diagrammatic view of a transformer and circuits embodying our invention.

Fig. 2 is a similar view of a modified form of our invention.

Our invention comprises, in general, a core member 1 having the customary pri-

mary winding 2 and secondary winding 3, together with a pair of auxiliary windings 4 and 5 that are connected to a common variable burden such, for example, as a variable resistor 6 and a measuring instrument 7.

The auxiliary windings 4 and 5 are mounted upon different legs of the transformer than is the primary winding 2. The auxiliary winding 4, however, is mounted on the same core leg as is the secondary winding 3. The variable resistor 6 may be connected wholly or partially in series with either of the auxiliary windings 4 and 5 by an adjustable contact element 8 adapted to selectively divide the resistor 6 into sub-divisions that are in series respectively with the auxiliary coils 4 and 5.

The measuring instrument 7, which is preferably a volt-meter, is connected across the terminals of the auxiliary winding 4 and may be calibrated to indicate the voltage across the secondary coil 3.

Upon energization of the primary winding 2 and with the adjustable contact in the mid-portion of the variable resistor 6, the flux threading the auxiliary winding 5 and that threading the auxiliary winding 4 and the auxiliary winding 3 are inversely proportional to their relative impedances. Since the impedances of the windings 4 and 5 are substantially equal, the winding 5 will be threaded by enough more flux than the winding 4 to compensate for the impedance of the secondary winding 3 with the result that the voltage across the auxiliary winding 5 will be slightly in excess of that across the auxiliary winding 4 and the reading on the instrument 7 represents the difference in potential across the terminals of the winding 4 which difference in potential is directly proportional to the potential across the secondary winding 3.

It is obvious that, as the movable contactor is moved to the left or the right along the variable resistor 6, the impedances of the coils 4 and 5 vary correspondingly with the result that the readings of the instrument 7 likewise vary in accordance with the potential of the secondary winding 3. Assuming the movable contact member to be at the extreme

left hand terminal of the variable resistor 6, the auxiliary winding 4 will be short-circuited and its impedance will be such as to preclude any flux traversing that leg of the transformer core 1 with the result that the voltage across the terminals of the secondary winding 3 is zero. At the same time, all of the flux generated by the primary winding 2 threads the auxiliary winding 5.

- 10 As the contact member 8 is moved along the variable resistor 6 to the right, the combined impedances of the auxiliary winding 4 and the secondary winding 3 decrease, an appreciable voltage appears across their terminals 15 which is registered by the measuring instrument 7. This voltage increases until the contact member 8 is moved to the extreme right of the variable resistor 6 when the impedance of the auxiliary winding 5 becomes so low as to preclude the passage of any flux therethrough, at which time all the flux traverses the windings 3 and 4. Under such conditions, the instrument 7 registers its maximum reading and the secondary winding 3 delivers 20 its maximum voltage.

Referring particularly to Fig. 2, we have shown a modified form of our invention in which the secondary coil is divided into two sections 11 and 12, section 12 being mounted 25 on the same leg as is the primary winding 2, while the section 11 is mounted on the same leg as is the auxiliary winding 4. By placing a reversing switch 13 across the terminals of one of the sections 12 or 13 so that they either 30 oppose or assist each other, it is possible to secure a voltage across the secondary winding of the transformer that varies over a range of voltage proportional to the sum of the voltages of the sections 11 and 12 or their difference.

40 It is to be understood that in case the sections 11 and 12 are capable of delivering the same voltage under one condition, the total secondary voltage delivered would be 45 zero and that under the other extreme condition, the secondary voltage would be twice the voltage of either coil. The interaction between the auxiliary winding 4 and the secondary winding 11 in this form of our invention 50 is similar to the interaction between the secondary winding 3 and the secondary winding 4 in the form of our invention shown in Fig. 1.

In the form of our invention shown in Fig. 55 2 the section 12 of the secondary winding will normally deliver its full potential by reason of its being mounted on the same core leg as the primary winding 2 while the voltage delivered by the secondary winding 11 varies 60 from zero to its maximum, in accordance with the position of the adjustable contact member 8 with reference to the variable burden 6. This maximum potential of the section 11 may oppose or be additive to the potential of 65 the section 12.

In both forms of our invention the auxiliary winding 5 is mounted alone on one of the legs of the core member 1.

It will thus be seen that we have provided a transformer for delivering a continuous but variable voltage for testing and measuring instruments that is characterized by employing an auxiliary winding to control the flux traversing it and a secondary winding and thereby vary the potential of the secondary winding.

70 It is to be understood that such changes may be made in the arrangement and disposition of the several parts of our invention as shall fall within the scope of the appended 80 claims.

We claim as our invention:

1. In a transformer, a core member comprising a plurality of legs, primary and secondary windings associated with said core member, auxiliary windings on a plurality of core legs, and a variable translating device connected to the auxiliary windings for controlling the flux distribution between the several legs associated with the auxiliary windings.

85 2. In a transformer, a core member comprising a plurality of legs, a primary coil mounted on one of the legs, a secondary winding mounted at least partially on a second leg, and auxiliary windings on certain of the transformer legs, one of the auxiliary windings being mounted on said second leg and adjustable means connected to the auxiliary windings for controlling the flux distribution 90 in the several transformer legs.

95 3. In a transformer, a core member comprising a plurality of legs, a primary coil mounted on one of the legs, a secondary winding mounted at least partially on a second leg, and auxiliary windings on certain of the transformer legs, one of the auxiliary windings being mounted on said second leg, and a variable burden connected to the auxiliary windings causing the auxiliary winding 100 associated with the secondary winding to operate between conditions of short-circuit and full burden whereby the voltage delivered by the secondary winding is varied.

105 4. In a transformer, a core, a primary winding thereon, an auxiliary winding and a secondary winding mounted on the same core leg, and means for varying the reactance of the auxiliary winding comprising a variable burden and an auxiliary winding mounted on another core leg and connected in circuit with the first-named auxiliary winding and the variable burden for controlling the reactance 110 of the first named auxiliary coil and thereby the voltage of the secondary winding.

115 5. In a transformer, a core structure, primary and secondary windings associated therewith, an auxiliary circuit comprising a plurality of windings mounted on different legs of the core structure, and means for pro- 120

portioning the flux traversing the respective last-named windings.

6. In a transformer, a core structure, a primary winding on one core leg, a secondary winding on another core leg, two auxiliary windings on separate core legs, and a burden in circuit with said auxiliary windings for inversely varying the impedance of said auxiliary windings.

10 7. In a transformer, a core structure, a primary winding on one core leg, a secondary winding on another core leg, auxiliary windings on separate core legs, a burden in circuit with said auxiliary windings, and
15 means for controlling the impedances of said auxiliary windings.

8. In a transformer, a core structure, a primary winding on one core leg, a secondary winding on another core leg, an auxiliary 20 winding on said other core leg, an auxiliary winding on another core leg, and a burden in circuit with said auxiliary windings.

9. In a transformer, a core structure having a plurality of core legs, a primary winding on one core leg, a secondary winding and an auxiliary winding on another core leg, a second auxiliary winding on another core leg and a variable burden in circuit with said auxiliary windings for controlling the 30 flux traversing said windings.

In testimony whereof, we have hereunto subscribed our names this 26th day of January, 1926.

JOHN F. PETERS.
ALBERT J. MASLIN.
